United States Patent Office.

SHEPHERD H. WHEELER, OF DOWAGIAC, MICHIGAN.

Letters Patent No. 65,974, dated June 18, 1867.

GATES.

The Schedule referred to in these Letters Patent and making part of the same.

TO ALL WHOM IT MAY CONCERN:

Be it known that I, SHEPHERD H. WHEELER, of Dowagiac, in the county of Cass, and in the State of Michigan, have invented certain new and useful improvements in "Gates," and do hereby declare that the following is a full, clear, and exact description thereof, reference being had to the accompanying drawings, and to the letters of reference marked thereon.

In the annexed drawings, making part of this specification, A represents a gate, which may be made in any of the known and usual ways in its general construction. A' represents a platform, which it is not necessary to have, but which I may employ. B and C represent the gate-posts. D represents an upright revolving post, which is placed a little in advance of and to one side of the rear post C. E represents a frame composed of two bars, which are pivoted together at their lower ends, but which are separated at their upper ends, which upper ends are confined to the extremities of a rocker, α . The convex side of the rocker is placed up, as represented. The post D has a bearing at its bottom, either in the platform A', or its equivalent, and at top in a cross-piece, which lies from it across the post C. A cleat is secured to the upper bar of the gate, as seen at α . The frame E is pivoted at its lower end to the post D, near its lower end, and the rocker α rests under and against the cleat α . One of the bars of the gate is a little prolonged at its forward end, so as to enter an opening in the front post B to act as a catch for the gate. The rear of the gate is placed between the two posts C and D, with its cleat resting upon the roller α . To open this gate the operator takes hold of it and pushes it backward until the projection e upon the top of the gate strikes that marked d on the post D. He holds up the front of the gate, while the rear rides upon the rocker α , rising as it moves back. When the two projections meet, he swings the gate around, the post D at the same time partially revolving, until it is at or about at right angles with its normal or shut position. As the rear of the gate is elevated by the frame E with its rocker, when it is being opened, it has of course a downward tendency when the front is lowered, so that it is easily shut. When in a shut position the bottom rail or bar of the gate rests in an opening in a piece placed under it, and it is thus kept steady.

Having thus fully described my invention, what I claim as new, and desire to secure by Letters Patent, is—

1. The frame E, with its rocker α , in combination with the revolving post D, as and for the purpose herein specified.
2. The combination of the frame E with the gate and its posts, and the cleat α , or its equivalent, as and for the purpose set forth.

In testimony that I claim the foregoing I have hereunto set my hand this 19th day of March, 1867.

SHEPHERD H. WHEELER.
